MARKING MACHINE

Philip A. Wooster, San Francisco, Calif.

Application January 21, 1932. Serial No. 587,936

4 Claims. (Cl. 33—36.)

This invention relates to a machine for placing marks as indicia on material so that the indicium bears a predetermined relationship to the width of the material.

5 The invention has been used with particular success in providing indicia on continuous roll towels which are dispensed from dispensing cabinets. Thus, as is disclosed in my copending application, Serial No. 569,746, such an indicium is employed on a continuous towel to indicate, by its position relative to the width of the towel, the quantity of undispensed towel remaining in the dispensing cabinet. Therefore, 10 I shall preferably disclose the machine of my invention as applied to the marking of toweling, altho it is useful for the marking of other articles or materials.

It is an object of the present invention to provide a machine for placing indicia on toweling in a simple and practical manner during manufacture thereof.

Another object of the present invention is to provide a machine for placing a series of a desired indicium upon a length of material in strip form, as toweling, so that the series are placed in a predetermined relationship on the bias of the toweling.

Another object of the present invention is to devise a machine for placing an indicium on a length of toweling so that the indicium extends diagonally between opposite corners of each towel.

The invention possesses other objects and features of advantage, some of which, with the foregoing, will appear in the following disclosure of the preferred form of marking machine of my invention shown in the drawing accompanying and forming a part thereof. In said drawing—

40 Fig. 1 is a front elevation of my machine;
Fig. 2 is a plan view of my machine;
Fig. 3 is a view, partly in section, taken along the line 3—3 of Fig. 2; and
45 Fig. 4 is a fragmentary side view of a portion of the machine.

In the preferred form of machine shown in the drawing, numerals 3 and 4 designate opposite sides of the end of frame 5 of a loom (not shown) upon which toweling 6 is manufactured. 50 The machine can, of course, be provided separately from the loom and in fact need not be cooperatively associated with the loom at all as the indicia can be applied to towels and toweling after manufacture and use as by a towel purveyor.

Roller 7 is carried by shaft 8 rotatably mounted in bearings 9 carried by frame 5. The towel passes over the roller to be subsequently handled as desired. Cooperatively adjacent roller 7, a slidable carriage, generally designated as 11, 60 is positioned. Carriage 11 includes arms 12 between which a member 13 is secured.

Member 13 is grooved as at 14 to receive a toweling marking means as removable die ring 16. Die ring 16 is rotatable in groove 14 and is positioned at an angle to the longitudinal axis or roller 7 for reasons that will be presently disclosed. The face of the die ring 16 can be such as to leave a design, figure, or trade-mark on the surface of the toweling with which it is 70 brought into contact or it can be plain so as to leave a single narrow band as that designated as 17 in Fig. 1. Ink is supplied to die ring 16 by felt inking roller 18 carried by the carriage 11. 75

Carriage 11 is mounted so that die ring 16 is normally maintained by the weight of the carriage in contact with the surface of the toweling passing over roller 7, arms 12 including at one end thereof bearings 19 by which arms 12 are 80 hinged on rod 20 positioned between frame sides 3 and 4. Arms 12 are slotted as at 15 at the other end thereof so that the arms are guided by rod 21 but are free therefrom to the extent that carriage 11 can be oscillated about rod 20 85 to remove the ring 16 from contact with the toweling.

In placing the preferred indicia on toweling it is desired that each indicium extend from one side diagonally to the opposite side over a distance corresponding to the length of the towel subsequently to be dispensed from a cabinet. I therefore provide means for causing relative movement between the means for marking the toweling and the toweling per se so that the 90 marking is placed diagonally on the toweling. I have found it more convenient to move the marking means transversely over the toweling during advance of the toweling over roller 7 and I therefore mount screw 22 for rotation in bearing blocks 23. 95

Bearing blocks 23 are slidable up and down in frame sides 3 and 4 by wedges 24 which are moved by levers 26. Levers 26 are hinged by pins 27 on brackets 28 secured to side frames 3 and 4 and are moved by rod 29 which is slidable in side frames 3 and 4. Collars 30 and 31 are secured to rod 29 and are engaged by arms 12 of carriage 11 so that when the carriage approaches the right hand end of rod 29, and contacts with 105 110

the collar 31, rod 29 is moved and wedges 24 raise bearing blocks 23 to lift both ends of screw 22. When the carriage reaches the left hand end of rod 29 and contacts with collar 31, the wedges 5 are withdrawn and both ends of screw 22 are lowered.

While screw 22 is driven by gears 32 removably secured to the screw, and gear 33, removably secured to shaft 8, the lift of wedges 24 is not sufficient to unmesh the gears, so that screw 22 is driven constantly from shaft 8. The lifting of screw 22 is effective to lift the carriage since the screw passes thru member 13 and contacts therewith when the wedges lift the bearing blocks for 15 the screw.

Rotation of screw 22 is selectively effective to move carriage 11 across toweling on roller 7. Thus, bell crank 34 is hinged on member 13 and includes finger 35 adapted to engage screw 22. A link 36 is hinged on bell crank 34 and spring 37 is positioned between arm 25 at the end of link 36 and bell crank 34 to provide a toggle-mechanism which can be actuated to move finger 35 positively to engage or disengage screw 22. A 20 member 38 is extended for only sliding movement thru member 13. Member 38 includes slotted portion 39 which engages the end of link 36 to actuate the toggle-mechanism, the movement of member 38, and consequently the movement of 25 the toggle-mechanism is limited by stops 40 on member 38. Movable flanges 41 are secured to screw 22 adjacent either end thereof, depending on the width of toweling. These collars are engaged by member 38 and move the member to 30 actuate the toggle-mechanism.

A cable 42 is attached to the carriage and passed over pulley 43 to a weight 44. This biases the carriage toward the left hand end of the screw. Stops 45 are fastened on rods 20 40 and 21 to limit movement of the carriage to the left.

In operation, with toweling advanced over roller 7 and with roller 7 rotating, carriage 11 is set at the side of the towel on the left hand side 45 of the machine. Member 38 engages the flange 41, on that side of the machine, to cause toggle mechanism to engage finger 35 with screw 22. Gears 32 and 33 drive the screw and with finger 50 55 engaged, move the carriage across the toweling, the ring 16 being pressed onto the toweling by the weight of the carriage to print the desired indicium on the toweling. Ink roller 18 supplies ink to the die ring as it rotates during travel over the toweling. Gears 32 and 33 and screw 22 are so related that carriage 11 is moved transversely of the toweling at such a rate that the 60 mark placed by ring 16 extends continually from one side of the towel diagonally to the other side on the bias of the towel, the face of the ring 16 corresponding substantially to the angle of the diagonal.

When the carriage approaches the other end 65 of the screw, member 38 engages the roller 41 and arm 12 engages a collar 30 on rod 29 to to slide the rod and forces wedges 24 to raise the screw and the carriage 11. At the instant that the carriage is lifted and the die ring 16 is free of the toweling, the toggle mechanism raises finger 35 and the carriage is pulled by weight 70 75 44 back to the left hand side of the machine. The rate of travel of the toweling is relatively slow so that because of the bias of weight 44, the carriage traverses the toweling substantially at a right angle to the longitudinal axis of the toweling.

Sliding movement of the carriage finally brings the arm 12 into engagement with the other collar 31 on rod 29 and causes the rod to slide and move the wedges and lower the screw 33 and carriage 11. The ink carrying die ring 16 is thus kept clear of the toweling during return across the toweling and is automatically lowered to begin placing another diagonal indicium.

As the carriage encounters stops 40, member 38 engages the other flange 41 to reset the toggle mechanism and lower the finger 35 into engagement with the screw. Because of the spring in the toggle mechanism, the toggle can be reset even tho the finger cannot enter the screw 80 85 thread until the screw rotates for nearly a whole revolution. As soon as the springs force finger 35 to engage the thread of the screw, the carriage begins its automatic transverse movement and the ink is again applied to the toweling to place a diagonal indicium thereon.

While I have disclosed the placing of the indicia on the toweling by an ink roller, the indicia can also be placed by sewing it into the toweling, or sewing a colored tape on the toweling. The sewing machine can be carried by the carriage 11 or can be fixed and the toweling moved past the machine. The ink die ring is, however, simple and effective and places a desired indicium on the toweling at the angle desired so that the indicium extends diagonally from one corner to another corner, at the opposite end of the towel. When the toweling is manufactured and comes from the loom in a substantially continuous length, the machine of 100 my invention automatically places the indicium diagonally of the toweling and over the predetermined length of the towel subsequently cut from the length of toweling, as appears in Fig. 1.

Various changes in mechanical detail can be 105 made without departing from my invention.

Having thus described my invention, what I claim as new and desire to secure as Letters Patent is—

1. In a machine of the class described, a roller 120 for supporting an advancing strip of material, a slidable carriage positioned cooperatively adjacent said roller, screw means for moving said carriage upon advance of said strip, means on said carriage for applying a mark to said strip, means for driving said screw means in accordance with advance of said strip so that said applying means applies a mark on the bias of said strip for a predetermined length thereof.

2. In a machine of the class described, means 125 for supporting an advancing strip of material, a slidable carriage positioned cooperatively adjacent said support means, means biasing said carriage toward one side of said sheet, screw means for moving said carriage upon advance of said strip toward the other side of said strip, means on said carriage for applying a mark to said strip, means on said carriage engaging said screw means and retaining said carriage against the bias of said biasing means during movement 130 of said carriage toward said other side of said strip, and means for driving said screw means.

3. In a machine of the class described, means 140 for supporting an advancing strip of material, a slidable carriage positioned cooperatively adjacent said support means, means biasing said carriage toward one side of said sheet, screw means for moving said carriage upon advance of said strip toward the other side of said strip, means on said carriage for applying a mark to 145 150

- 5 said strip, and means on said carriage engaging said screw means and retaining said carriage against the bias of said biasing means during movement of said carriage toward said other side of said strip, said engaging means including toggle mechanism, and a spring biasing said mechanism to maintain said engaging means selectively in or out of contact with said screw means.
- 10 4. In a machine of the class described, means for supporting an advancing strip of material, a slidable carriage positioned cooperatively adjacent said support means, means biasing said carriage toward one side of said sheet, screw means for moving said carriage upon advance of
- 15 said strip toward the other side of said strip, means on said carriage for applying a mark on said strip, and means on said carriage engaging said screw means and retaining said carriage against the bias of said biasing means during movement of said carriage toward said other side of said strip, said engaging means including toggle mechanism, a spring biasing said mechanism to maintain said engaging means selectively in or out of contact with said screw means, and means to engage said toggle mechanism at either end of said screw means to actuate said mechanism to secure selective connection of said engaging means and said screw means.
